UNITED STATES PATENT OFFICE.

JOHN L. FLANNERY, JR., OF CHICAGO, ILLINOIS, ASSIGNOR TO THE BOYE NEEDLE COMPANY, OF CHICAGO, ILLINOIS, A CORPORATION OF ILLINOIS.

COMMODITY-CABINET.

1,361,451.

Specification of Letters Patent.

Patented Dec. 7, 1920.

Application filed April 4, 1919. Serial No. 287,539.

To all whom it may concern:

Be it known that I, JOHN L. FLANNERY, Jr., a citizen of the United States, residing at Chicago, in the county of Cook and State 5 of Illinois, have invented a new and useful Improvement in Commodity-Cabinets, of which the following is a specification.

This invention relates particularly to cabinets adapted to the purpose of storing 10 and displaying small articles of merchandise; and the primary object is to provide a cabinet of simple and cheap construction which is well adapted to such purpose.

In the embodiment of the invention illustrated, the cabinet is adapted to the purpose 15 of storing and displaying small articles of merchandise, such as snap-buttons or other forms of dress fasteners, or any other small articles of merchandise adapted to be 20 mounted on cards.

The invention is illustrated in its preferred embodiment in the accompanying drawings, in which—

Figure 1 represents a perspective view of 25 a commodity cabinet constructed in accordance with the invention, one closure of the cabinet being shown in open or standing position; Fig. 2, a sectional view of the improved cabinet, the section being taken as 30 indicated at line 2 of Fig. 3; and Fig. 3, a vertical sectional view parallel with the front of the cabinet, the section being taken as indicated at line 3 of Fig. 2.

In the construction illustrated, A represents a casing equipped with an upper closure A' and a lower closure A². The cabinet is divided, by suitable partitions, into a series of compartments 1, 2, 3, and 4, which 35 preferably incline rearwardly and upwardly 40 and are arranged in stepped relation. The series of compartments 1 are provided with a rear inclined wall 1^a; and the individual compartments have side walls 1^b. Similarly, the series of compartments 2, 3 and 4 45 have the rear walls 2^a, 3^a, and 4^a, respectively, and the individual compartments of these series have the lateral walls 2^b, 3^b, and 4^b, respectively.

The compartments are of a suitable width 50 to receive display cards 5, which may be of any suitable design. Thus, the card 5 shown in Fig. 3 has its face marked with a design indicated by 5^a; and the card is shown as having mounted thereon snap-buttons or dress-fasteners 5^b. The recepta-

cles, or compartments, preferably are bottomless, except that there are provided in the lower portions of the compartments card-supporting strips 6. These strips are disposed edgewise, and preferably incline 60 rearwardly and downwardly. Thus, they afford shoulders which are adapted to support the cards 5 which, for this purpose, are provided at their lower edges with slots 7.

Display cabinets of this construction may be furnished by manufacturers of small articles of merchandise to dealers throughout the country; and one purpose of the construction is to provide against improper use 70 of the cabinet or against unauthorized or fraudulent use of the cabinet. Thus, a manufacturer who furnishes the cabinets to dealers gratis, that is to say, with the understanding that the cabinet shall be used only 75 in displaying and selling merchandise of such manufacturer, may supply cards specially adapted for use in the cabinet, and may guard against unauthorized use of the cabinet.

It will be noted, from Fig. 2, that the disposition of the compartments is such as to provide a space 8 beneath the compartments. Access to this space may be had by means of a door 9 with which the rear wall 85 9^a of the cabinet is provided. The upper closure A' of the cabinet preferably comprises a transparent wall 10 and a frame having side members, or flanges, 10^a, a rear upper member, or flange, 10^b, and a lower 90 cross-member, or stop, 10^c. The closure A² comprises a transparent member 11 and a frame having side-members, or flanges, 11^a, a lower member, or flange 11^b, and an upper cross-member, or stop 11^c, which is located 95 adjacent the cross-member 10^c. The closure A' has its side-flanges joined, by pivot connection 12, to the rear upper portion of the cabinet. The closure A² has its side flanges connected, by pivots, 13, to the lower front 100 portion of the cabinet. Thus, the upper closure A' is adapted to be thrown upwardly and rearwardly to the standing position shown in Fig. 1, in which position the flange 10^b will bear against the rear wall 4^a of the 105 cabinet. The closure A² may be opened by swinging it upwardly and forwardly. Thus, access to the compartments of the cabinet is gained from the top of the cabinet by opening the closures.

As has been indicated, the supports for the cards are so constructed as to require the use of special cards in the cabinet. Preferably this is done by recessing, or cutting 5 away, the lower edge-portions of the cards. Any suitable expedient may be adopted, however, for requiring the use of a specially shaped card. It is desirable, in order that disarrangement of cards may be avoided, 10 that the supporting members 6 shall incline rearwardly and downwardly; also, that the compartments shall have back walls for the cards to bear against and lateral walls to prevent the cards from tipping on their 15 supports. This is more especially desirable because it is desirable to have the slots 7 at the lower edges of the cards somewhat tapering so that the cards can readily be placed upon the supporting strips. The means for sup- 20 porting the cards may be varied, of course. It is desirable to employ supporting means, however, which will permit portions of the cards to depend below the supporting means. Thus, in Fig. 3, the upper wall of the slot 7 25 of the card rests upon the upper edge of the strip 6, while portions of the card depend below the upper edge of the strip 6. Because of the fact that the compartments are quite shallow, it would not be feasible to 30 substitute ordinary rectangular cards for the slotted cards shown, as the cards would fall out of the receptacles and become dis- 35 arranged. It will be noted, for example, that the rear wall 1^a of the front series of compartments 1 forms the front wall for the lower portions of the series of compartments 2; and thus it will be seen that the compartments are open both at their upper ends and at the front sides of their upper portions. 40 The construction described is simple and well adapted to the display of cards or paper slips having mounted thereon small articles of merchandise; and the cabinet is adapted to prevent fraudulent practices, as 45 where a merchant receives a cabinet bearing the name of a reputable manufacturer and marked to indicate that only the goods of such manufacturer are to be displayed in and sold from the cabinet. The special 50 form of card required for the cabinet will prevent an unscrupulous merchant from employing the cabinet, except in connection with cards especially adapted for use in connection therewith. The cards may be 55 employed as mountings for various small articles of merchandise, which, as shown in the illustration selected, may be readily detachable from the cards. Thus, the cards may be used continuously as mountings by applying 60 fresh articles thereto, as may be necessary, or fresh cards may be substituted for replacement or renewal purposes, as desired.

As illustrated in Fig. 1, the side walls of the cabinet may be equipped with stops 14

adapted to support the closures when they 65 are in the closed position.

The foregoing detailed description has been given for clearness of understanding only and no unnecessary limitation should be understood therefrom, but the appended 70 claims should be construed as broadly as permissible in view of the prior art.

What I regard as new, and desire to secure by Letters Patent, is:

1. A cabinet comprising several series of 75 upwardly and rearwardly inclined compartments having the lower portion of one series disposed behind the upper portion of the preceding series, said compartments being provided with open upper ends and open 80 front sides at their upper portions and having central card-supporting strips which incline forwardly and upwardly and are adapted to engage central notches of cards 85 adapted to said receptacles.

2. A cabinet comprising several series of upwardly and rearwardly inclined compartments having the lower portion of one series disposed behind the upper portion of the preceding series, said compartments being 90 provided with open upper ends and open front sides at their upper portions and having card-supporting shoulders which are arranged to provide spaces into which portions of cards may project below said 95 shoulders.

3. A cabinet comprising several series of upwardly and rearwardly inclined compartments arranged in stepped relation with the lower portion of one series disposed behind 100 the upper portion of the preceding series, said compartments being open at their upper ends and at the front sides of their upper portions and having their bottoms provided with forwardly and upwardly inclined card- 105 supporting strips, an upper inclined closure provided with a transparent wall and pivotally connected with the rear upper portion of the cabinet and a lower inclined closure having a transparent wall and pivotally connected with the lower portion of the cabinet, 110 said closures being adapted to swing in opposite directions in opening the cabinet.

4. In combination, a cabinet comprising several series of upwardly and rearwardly 115 inclined compartments, arranged in stepped relation; said compartments having open upper ends and open front sides at their upper portions and said compartments having, also, card-supporting shoulders which 120 are arranged to provide spaces into which portions of cards may project; and card-like mountings contained in said compartments and having shoulders engaging said first-named shoulders and having portions 125 extending into said spaces, said mountings being adapted to support articles on display.

5. In combination, a cabinet comprising

several series of upwardly and rearwardly inclined compartments having the lower portion of one series disposed behind the upper portion of the preceding series, said 5 compartments being provided with open upper ends and open front sides at their upper portions and having central card-supporting strips which incline forwardly and upwardly and are adapted to engage 10 central notches of cards adapted to said receptacles; and mountings for articles of display, said mountings comprising cards adapted to said compartments and having central notches engaging said card-support- 15 ing strips.

6. In combination, a display cabinet comprising a compartment having an open upper end and open front side and provided in its lower portion with a card-supporting 20 shoulder and a space below said shoulder into which a portion of a mounting-card may extend, and card-like mountings con-

tained in said compartment and having a shoulder resting on said first-named shoulder and having a portion extending into said 25 space, said mountings being adapted to support articles on display.

7. In combination, a cabinet comprising several series of compartments arranged in stepped relation, said compartments having 30 open upper ends and open front sides at their upper portions and said compartments having, also, card-supporting strips disposed in their lower portions and arranged to provide spaces into which portions of card- 35 mountings may project; and card-like mountings contained in said compartments and provided with slots affording shoulders resting on said card-supporting strips, the lower portions of said mountings extending 40 into said spaces, and said mountings being adapted to support articles on display.

JOHN L. FLANNERY, JR.
